C. F. FLEMMING.

TRAIN DERAILER.

APPLICATION FILED SEPT. 9, 1913.

1,079,230.

Patented Nov. 18, 1913.

UNITED STATES PATENT OFFICE.

CHARLES F. FLEMMING, OF WASHINGTON, DISTRICT OF COLUMBIA.

TRAIN-DERAILER.

1,079,230.

Specification of Letters Patent.

Patented Nov. 18, 1913.

Application filed September 9, 1913. Serial No. 789,005.

To all whom it may concern:

Be it known that I, CHARLES F. FLEMMING, a citizen of Washington, in the District of Columbia, have invented certain new and useful Improvements in Train-Derailers, of which the following is a full, clear, and exact specification.

This invention relates to derailers for preventing rear end collisions of railway trains, 10 locomotives or cars.

In case a train runs past a signal and is in danger of colliding with a train ahead, the railroad companies do not hesitate to derail the rear train when possible in order 15 to prevent it also wrecking the train ahead. Indeed, some of the railroads have installed derailing devices at intervals along their tracks, especially in yards and depots, for this express purpose.

20 It is the object of the present invention to provide a device which is not subject to anybody's supervision and yet is sure in its operation whenever occasion arises.

Other objects will become apparent as the 25 description proceeds.

The invention will be first hereinafter described in connection with the accompanying drawings, which constitute a part of this specification, and then more specifically set 30 forth in the claims at the end of the description.

In the accompanying drawings wherein similar reference characters are used throughout the several views for designating 35 corresponding parts; Figure 1 is a side elevation of a derailing device constructed in accordance with my invention, and attached to the end of a train; Fig. 2 is a plan view of the derailing device as a whole; Fig. 3 40 is an enlarged broken plan view of the derailing shoe alone; Fig. 4 is a cross section of the shoe on the line IV—IV of Fig. 3, and Fig. 5 is an end view of the shoe as it appears when forced down upon the rail after 45 the front wheels of a locomotive or train have passed up onto it.

As clearly indicated in Fig. 1, my improved derailler 1 is designed to be attached to the rear end of a train 2 by one or more 50 connecting rods 3 of suitable length so that the derailler will be drawn along behind the train at say about thirty yards to the rear of the same. Each of the connecting rods 5 may be about one and a half inches in diameter and about five yards long. The front rod is adapted to be connected to the cou-

pling 4 on the rear car of the train, while the rear rod is attached to the derailler and the rods are connected to each other by suitable couplings as the pins 5.

The derailler comprises a body 6, which may be mounted on an ordinary car truck 7, and a derailing shoe 8 which is normally supported a little above the track 9 by a bracket secured to the body 6 and consisting 60 of a downwardly and rearwardly curved bar or member 10 and a brace 11. The member 10 is rigidly fastened at its upper end to the rear portion of the body 6, but the brace 11 is hinged or pivoted to both the body and 65 said member 10. A spring 12 is interposed between the member 10 and the body, preferably at a point just above where the brace is attached to the latter, and aids in supporting the shoe 8, above the rail. The 70 spring may be guided on two pins 13, one attached to the body and the other to the member 10, as shown in Fig. 1. It will be understood that the body is sufficiently 75 weighted to insure it keeping on the track, 80 and that it may be suitably shaped to reduce the obstruction offered to the wind, as by sloping its top surface upwardly and rearwardly, as illustrated at 6a.

The shoe 8 has a groove 14 in its upper 85 surface starting at its rear end in line with the path of the flanges of the wheels of a train, and terminating at the front end on its outer side for the purpose of carrying the wheels over the rail. The front portion of 90 this groove opens into a laterally inclined or depressed portion 15a in the upper surface of the shoe and sloping toward the outer side thereof. The portion 15 of the upper surface of the shoe, which lies between said depression 15a and the rear end 95 of the shoe is inclined, as shown in Figs. 3, 4, and 5, to carry the tread of the wheel while the flange thereof is riding in the groove 14 to the point where it opens into 100 the depression 15a. When the flange reaches the depression, the weight of the locomotive or car will cause the wheel to slide down the lateral incline thereof and drop on the outside of the rail. The under face of the shoe 105 is channeled longitudinally, as at 16 to fit down over the head of the rail. The side walls of this channel are slightly inclined to agree with the form of the ordinary rail head, and are provided with vertically disposed serrations 17 leaving flat-faced projections or teeth 18 adapted to grip the sides 110

sufficiently weighted to keep it on a track, said body being shaped to reduce the resistance offered by it to the wind, and a derailing shoe yieldingly supported from the body so as to be normally carried slightly above one of the rails of a track in position to be depressed into operative position when engaged by the front wheel of a locomotive or car approaching from the rear.

10 10. A derailer comprising a body, a supporting member fastened to the upper part of the body and extending downwardly and rearwardly therefrom, a derailing shoe sup-

ported on the rear end of said member, a brace hinged to the lower portion of the body and also to an intermediate portion of the supporting member and a spring arranged between said supporting member and the body, all for the purposes specified.

In testimony whereof I have signed my name to this specification in the presence of two attesting witnesses.

CHARLES F. FLEMMING.
